A. CAMPBELL

DUMP CAR DOOR OPERATING MECHANISM

Filed Feb. 6, 1925

UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP-CAR-DOOR-OPERATING MECHANISM.

Application filed February 6, 1925. Serial No. 7,284.

This invention relates to improvements in dump car door operating mechanisms and forms a continuation in part of my pending application, Serial No. 691,830.

5 An object of this invention is to provide an improved form of door operating and locking mechanism which may be conveniently disposed in a restricted space and safely operated.

10 A more specific object of the invention is to provide a safety device for the operation of dump car doors from the side of cars and to so dispose and adapt the parts that they will be within the clearances required by law and be conveniently situated to permit ease of operation and safety to the operator and yet possess the strength and ruggedness to withstand the unusually severe service to which such parts are commonly subjected.

15 The invention furthermore consists in the improvements in the parts and devices and in the novel construction of the parts and devices herein shown, described and claimed.

20 In the drawings forming a part of this specification, Figure 1 is a vertical transverse sectional view through a portion of a car showing my improvements associated therewith and also showing so much of the side wall of the car and door construction as will show the relation of the parts. Fig. 2 is a side elevational view of a portion of the car showing the operating and locking mechanism illustrated in Fig. 1. Fig. 3 is a longitudinal sectional view of the door lifting mechanism taken on a line corresponding substantially to line 3—3 of Fig. 1. Fig. 4 is a perspective view of the outer end of the shaft. And Fig. 5 is a sectional view taken through the shaft rotating mechanism, substantially on the line 5—5 of Fig. 2.

25 In the drawings, 10 denotes one of the side walls of the car, 11 a fixed floor section extending longitudinally of the car adjacent the door opening, 12 a fixed floor section extending transversely of the car adjacent the free edge of the door, and 13 a pivoted floor door arranged to lie substantially flush with the floor of the car when the door is in closed position. The door 13 is pivoted along an axis (not shown on the drawing) extending transversely of the car, and ordinarily there will be two doors disposed in alignment on opposite sides of the

center sill and operated in unison by a common shaft, a portion of which is shown at 55 14. Sliding latches 15, and connecting means, usually in the form of self-locking linkage mechanism 16, which is adapted to wind on a polygonal drum 116, are generally provided for maintaining the door in closed 60 position, the construction being such that when the doors are closed and locked in position as indicated in Fig. 3, it is necessary to rotate the shaft 14 toward the adjacent edge of the door until the point of 65 connection between the latch 15 and the linkage 16 moves to one side of the center of the shaft, when the weight of the door and lading will be sufficient to cause the shaft to unwind the linkage and quickly open 70 the door 13. The shaft 14 is disposed parallel to the free edges of the sets of pivoted doors in a plane below the doors and beyond the path of movement of the doors to permit the same to clear the shaft and associated parts. In actual practice, in a car such as indicated in the drawings, the shaft 75 14 passes through the centersills of the car (not here shown) and is mounted in suitable 80 bearings.

85 At each side of the car, the shaft extends through the lower portion of the car side wall 10 and is mounted in a suitable bearing 17 which is secured to the bottom chord 110 of the side wall of the car. The chord 110 preferably consists of an angle member having one flange 18 disposed in a vertical plane and another flange 19 disposed on a horizontal plane. In cars of this type it is customary to extend the side wall of the car below 90 the floor level of the car, thereby providing additional depth for the said side, and as shown in Figs. 1 and 2, it will be noted that the shaft 14 passes through the vertical flange 18 of the angle which is cut out for 95 this purpose and the bottom chord is suitably reinforced at such a point by extending the bearing member 17 to either side of the shaft and securing the same to the chord 110 at its horizontal and vertical flanges as shown at 20, and also to the plate 21 of the car side wall as shown at 22.

100 The shaft rotating mechanism is disposed exteriorly of the side wall of the car, and the preferred construction includes a ratchet wheel 23, or other similar suitable toothed

member, which is non-rotatably mounted on the shaft 14, preferably by forming the portion of the shaft adapted to receive the ratchet of square section, as indicated at 24, and 5 providing a hole in the ratchet wheel of corresponding shape.

Rotatably mounted with respect to the ratchet wheel 23, is the shaft rotating mechanism proper, designated broadly by the reference character A. Said mechanism includes an actuating device comprising an inner wall 25, and an outer supporting plate providing a wall 26, such walls being disposed on opposite sides of the ratchet wheel, 10 and united by means of rivets 27, each of the rivets being encircled by a boss 28, so as to effectively space the inner and outer walls. Each of the bosses 28 is preferably formed integrally with one of said walls, and the end 15 thereof extended for a distance into a recess 29, formed in the other of said walls, for the purpose of lessening the strain on the rivets 27, as rotation of the mechanism is effected. The outer wall 26 of the actuating mechanism 20 is provided with an integrally formed squared portion 30, which is adapted to receive the end of an operating wrench, whereby said actuating device may be rotated. The squared portion 30 on the wall 26 is 25 provided with an opening for the reception of a circular portion 31, forming part of the shaft, 14, the circular portion providing a hub on which the outer wall of the actuating device is mounted so as to rotate freely. The inner wall 25 of the actuating device is 30 also pivotally supported upon the shaft 14, in a manner hereinafter described. A pawl 32 is pivotally mounted on one of the bosses and by means of this pawl, operative engagement may be established between the 35 rotatable mechanism A and the ratchet wheel 23.

Co-operable with the ratchet wheel 23 is 40 a locking pawl 33 which is adapted to be locked by means of a cam 34. Said members 33 and 34 are respectively mounted on bosses 35—35 formed integrally with a base plate 36 which is secured to the car structure directly by means of a rivet 37 and also by means of rivets 38 which pass through 45 the said bosses, which rivets also serve to secure in position a strap 39 which extends over said pawl 33 and cam 34, and maintains both of said members against lateral 50 displacement. The base plate 36 is preferably mounted on the car structure independently of the shaft, and the rivets 37 and 38 provide an excellent anchorage on the car structure for the same. The locking pawl 55 33 and the operating pawl 32 operate on the ratchet wheel 23 and are substantially in the same vertical plane, and therefore in order to provide the greatest possible extent of sweep for the pawl 32 the bosses 28—28 are 60 disposed relatively close together, being 65

spaced apart substantially 90° with reference to the pivotal axis of the actuating device, as indicated at 139. This angular relation may be varied considerably but generally speaking it is desirable to dispose the 70 attachments uniting the respective plates 25 and 26 within an arc of 180 degrees.

The mechanism A is spaced outwardly from the car wall a sufficient distance to permit of securing the ratchet wheel 23 to the 75 shaft 14, and for this purpose a hub 40 formed integrally with the said ratchet 23 is extended lengthwise of the shaft and a pin 41 passes through the said hub 40 and the shaft 14, said pin 41 being disposed immediately adjacent the inner wall 25 of the mechanism. The inner wall 25 is rotatably mounted upon the hub portion 40, and as previously described the outer wall 26 of the mechanism is mounted on the circular end 80 31 of the shaft, the actuating device being thus pivotally carried by the shaft 14. In order to dispose the pawl 33 and cam 34 in the same vertical plane as the ratchet wheel 23, the base portion 36 is spaced outwardly 85 from the side wall by means of enlarged bosses as indicated at 42. The rotating mechanism A may be assembled with the ratchet wheel 23 and inserted on the shaft as a self-contained unit and locked in position 90 by the pin 41.

The operation of the device is as follows: Assuming the parts to be in the position shown in Figs. 1 and 2, the operator, after disengaging the locking cam 34, from the 100 pawl 33, and swinging the latter free of the ratchet wheel 23, and placing the pawl 32 in engagement with ratchet wheel 23, engages the squared portion 30 of the mechanism with a wrench, effecting rotation of the shaft 14 in a counter-clockwise direction, thereby 105 forcing the latch 15 rearwardly until the same is moved to one side of the axis of the shaft, when the weight of the door and lading will be sufficient to open the door and 110 straighten the linkage 16. As the weight of the door and lading operate to unwind the shaft, the latter is rotated at great speed but the pawl 32 will ride freely over the ratchet wheel 23 so that the mechanism A, 115 and consequently the wrench or tool in the hands of the operator, will not be carried in unison therewith, but on the contrary will be held steady while the opening movement of the door is being completed. The door 120 closing operation is the reverse of the opening operation, the locking pawl 33 being turned into engagement with the ratchet wheel, and the pawl 32 engaged therewith to rotate the shaft 14 in the opposite direction until the doors are drawn to closed position.

Although I have shown and described herein what I now consider preferred embodiments of the invention, the same are 125

merely illustrative and I contemplate all changes and modifications that come within the scope of the claims appended hereto.

I claim:

5. 1. In a car door operating mechanism, the combination with a winding shaft; of a toothed member rigid with respect to the shaft; a rotatable member mounted on the end of the shaft, said member having a portion on the end thereof disposed in the plane of the operating shaft and adapted to be engaged by an operating tool; and a pawl member carried by the rotatable member adapted to engage with the toothed member. 10
15. 2. In a car door operating mechanism, the combination with a winding shaft; of a ratchet wheel member fixedly mounted on the shaft; an actuating device rotatably mounted on the shaft and having inner and outer walls disposed on opposite sides of said ratchet wheel, the outer wall having a projection formed thereon adapted to be engaged by an operating tool, said projection being co-axially disposed with reference 20 to said shaft; and an offset pawl member pivotally mounted between the walls of actuating device and adapted to co-act with the ratchet wheel to rotate the shaft. 25
3. In a car door operating mechanism, the combination with a winding shaft; of a toothed member fixedly mounted on the shaft; a rotatable member mounted on the shaft and presenting inner and outer walls respectively disposed on opposite sides of 30 the toothed member; the outer wall having an outward lateral extension adapted for engagement by an operating tool, said extension being hollow and journalled directly on the end of the shaft; and a pawl member 35 disposed between the walls and pivotally mounted on the rotatable member and adapted to co-act with the toothed member to rotate the shaft. 40
4. In a railway car, the combination with a dump door; of an operating shaft; a ratchet wheel fixedly mounted thereon; shaft rotating means including inner and outer walls disposed respectively on opposite sides of the ratchet wheel; connecting 45 means between the respective walls, said means including a plurality of bosses adapted to space the walls apart and securing means extending through the bosses to unite the walls, said bosses being disposed beyond the periphery of the ratchet wheel and contained within an arc of 180°; an operating pawl carried by one of said 50 bosses; and a locking pawl pivotally mounted on the car structure and adapted to 55 also engage the ratchet wheel and lock the shaft against rotation. 60
5. In a car door operating mechanism, the combination with a winding shaft; of a ratchet wheel non-rotatably mounted on the shaft; an operating member rotatably 65
- mounted on the shaft and having a pawl member adapted to engage with the ratchet wheel; locking means mounted on the car structure independently of the shaft, said means including a base plate having bosses 70 formed integrally therewith and a locking pawl and cam respectively pivotally mounted on the said bosses, said pawl being adapted to engage the said ratchet wheel to lock the shaft against rotation and the cam 75 being adapted to lock the pawl relatively to the ratchet wheel; a strap adapted to extend over the said pawl and cam; and means passing through said bosses and strap for securing the locking means to the car structure. 80
6. In a railway car, the combination with the side wall of the car; of a door hinged on an axis extending transversely of the car; an extension on the side wall of the car depending below the plane of the door; shaft supporting means disposed inwardly of the car wall; and a ratchet wheel fixedly mounted on the shaft outwardly of the car 85 wall and adapted to be engaged for rotating and locking the shaft; a base plate mounted on the car wall independently of the shaft and having a locking pawl and locking cam pivotally mounted thereon, said locking pawl being adapted to engage the ratchet wheel 90 and be locked in position relatively thereto by the car; and shaft rotating means having inner and outer walls pivotally mounted on opposite sides of said ratchet wheel and having a pawl adapted for engagement with the said ratchet, said outer wall having a lateral extension disposed co-axially with said shaft and adapted for engagement by an operating tool. 95
7. In a railway car the combination with the side wall of the car; of a door hinged on an axis extending at right angles to the side wall of the car; an extension on the side wall of the car depending below the plane of the door; a bottom chord including an angle 100 shaped member having the vertical flange secured to the car side and the horizontally extending flange forming the lower margin of the said side wall; a shaft disposed adjacent the free edge of the door and passing through the vertical flange of the angle member; a bearing for the shaft secured to both vertical and horizontal flanges of the angle and also secured to the car wall independently of the angle member; and shaft 105 rotating and locking means disposed outside of the car wall. 110
8. In a railway car, the combination with the side wall of the car; of a door hinged on an axis transversely of the car; an extension on the side wall of the car depending below the plane of the door; shaft supporting means disposed inwardly of the car wall; and shaft rotating and locking means being 115 disposed outwardly of the car wall, said 120
- 125
- 130

shaft rotating means including a ratchet wheel member on the shaft and a member rotatably mounted relatively thereto and adapted to engage the same through the medium of an operating pawl, the said shaft locking means including a base plate mounted on the car wall independently of the ratchet wheel and carrying a locking pawl and a locking cam, said locking pawl being adapted to engage the said ratchet wheel.

9. In a device of the character described, including a clutch mechanism adapted for the operation of a car door operating shaft, said mechanism comprising a ratchet wheel adapted to be fixedly mounted on the operating shaft, said ratchet having on one side thereof a hub portion extending laterally from the ratchet wheel; inner and outer walls disposed on the respective sides of the ratchet wheel, the inner of said walls being rotatably mounted on the said hub portion and the outer of said walls being formed with an extension adapted to be engaged by an operating tool for rotating the mechanism; spacing means between the respective walls including bosses fixed relatively to one of the members; means extending through the said bosses to unite the walls; and a pawl pivotally mounted on one of the bosses adapted for clutch engagement with the ratchet in either direction.

10. In a device of the character described, including a clutch mechanism adapted for the operation of a car door operating shaft, said mechanism comprising a ratchet wheel

adapted to be fixedly mounted on the operating shaft, said ratchet having on one side thereof a hub portion extending laterally from the ratchet wheel; inner and outer walls disposed on the respective sides of the ratchet wheel, the inner of said walls being rotatably mounted on the said hub portion and the outer of said walls being formed with an extension adapted to be engaged by an operating tool for rotating the mechanism; spacing means between the respective walls including bosses fixed relatively to one of the members; means extending through the said bosses to unite the walls; and a pawl pivotally mounted on one of the bosses adapted for clutch engagement with the ratchet in either direction.

11. In a winding mechanism for dump car doors, the combination with a shaft provided with a ratchet wheel; of an actuating device pivotally mounted with respect to said shaft and having portions disposed in offset position relative to said shaft; a pawl pivotally mounted on one of said offset portions and adapted for engagement with said ratchet wheel; and means on said actuating device disposed co-axially with said shaft and adapted for the reception of an operating element.

In witness that I claim the foregoing I have hereunto subscribed my name this 4th day of February, 1925.

ARGYLE CAMPBELL.
